UNITED STATES PATENT OFFICE.

HIRAM W. BLAISDELL, OF LOS ANGELES, CALIFORNIA.

EXCAVATOR.

No. 884,559.

Specification of Letters Patent. Patented April 14, 1908.

Application filed May 31, 1906. Serial No. 319,637.

To all whom it may concern:

Be it known that I, HIRAM W. BLAISDELL, a citizen of the United States, residing at Los Angeles, in the county of Los Angeles and State of California, have invented certain new and useful Improvements in Excavators; and I do hereby declare the following to be a full, clear, and exact description of the invention, such as will enable others skilled in the art to which it appertains to make and use the same.

This invention is an improvement in apparatus for discharging the contents of tanks or vats used in hydro-metallurgical processes and has among other objects the providing of an appliance of this class that shall perform its function with a minimum expenditure of power.

Another object is to provide an apparatus that shall be capable of working close to the wall of the tank in which it is used.

A further object of the invention is to provide an apparatus that can be easily transported and placed in working position in any one of a number of vats or receptacles, as may be required.

Another object is to provide an apparatus wherein the vertical movement of the excavator devices can be stopped at a predetermined point, so that they shall not injure the filter at the bottom of the vat.

In the drawings accompanying, and forming a part of, this specification Figure 1 is a plan of a portion of a vat, with a part of the apparatus therein, portions being broken away; Fig. 2 is an elevation of the apparatus, with portions broken away; Fig. 3 is a side elevation of the upper portion of this invention. Fig. 4 is a section of the cross head; Fig. 5 is a detail of the reversible pawl. Fig. 6 is a detail of an alternative form of cutter, which may be used in place of those shown in the preferred construction.

Reference numeral 1 designates a tank or vat such as is used in hydro-metallurgical processes, adjacent to the sides of which, or a row of which, timbers 2 may be supported on posts 3. Rails 4 are fastened to timbers 2 and on them wheels 5 of a traveling structure 6 are adapted to travel. The central portion of traveling structure 6 has a bearing 7, while a truss 8 carried by said traveling structure supports the upper end of shaft 9.

The hub of a bevel gear 10 is adapted to turn in bearing 7. Shaft 9, Fig. 4, passes through the hub of gear 10, being splined

therin and having formed integral therewith a collar 11, which is supported in a yoke 12, upon washers 13, 14, 15, and 16, formed of different materials in order to diminish wear and friction.

Yoke 12 has trunnions 17 which bear in blocks 18 attached to cross head channels 19. Upright channels 20 are attached to the traveling structure near its middle portion, being braced by and forming part of truss 8, and form guides for the cross head 19.

Bevel gear 10 is driven by a bevel pinion 21 on the end of shaft 22, the other end of which carries a spur gear 23, driven by a spur pinion 24, upon a shaft 25, being coupled to the latter at will by a clutch 26. The outward end of shaft 25 has keyed to it a pulley 27 which may be operated by a motor 65 mounted upon the traveling structure.

The lower end of shaft 9 carries a frame 28 having standards 29 on which are rotatably mounted disks or revolving cutters 30, 31 and 32, arranged with their horizontal diameters at an angle to the direction of their travel. For clearness of illustration, only a limited number of disks is shown, but in practice a much larger number will be employed.

Experiments have proved that the best results are attained by having the disks 30 nearest the center, formed flat with their surfaces vertical. The next in sequence, 31, are also preferably vertical but concavo-convex in form, the concave sides being nearest the shaft 9. As the distance of the disks from the center increases, it is of great advantage to incline them from the vertical, the tops of the disks being farthest from the shaft 9, as in 32.

A scraping disk 33 supported adjustably by a standard 34, is inclined to the vertical in an opposite direction to the disks 32 so as to enable it to work close to the wall of the vat. This disk is preferably flat and may or may not have its horizontal diameter inclined to the direction of travel.

Disk 35 is placed near the end of one of the arms other than that which carries disk 33, and is preferably vertical, so that it will not interfere with the sloping disk adjacent to it.

The inner end of shaft 25 carries an adjustable throw crank 36, which is connected by means of a pitman 37 with a reciprocating lever 38, loosely mounted on a shaft 39. In reciprocating lever 38 is mounted a pawl 40, Fig. 5, the lower part of which, 41, may be

square and the end beveled. A spring 42 is arranged to press the bevel end of the pawl 40 into the teeth of a ratchet wheel 43. A handle or hand wheel 44 may be provided at the end of pawl 40 by means of which the latter may be drawn out until the square part 41 clears the square hole in lever 38, in which it normally rests, whereupon it may be reversed. It is to be understood that no claim is made on this particular form of ratchet and any other suitable form may be adopted.

One member of a clutch 45 may be attached to ratchet wheel 43 the other member being splined to shaft 39. Actuating fork 46 of said clutch may be attached by means of a chain or other connection 47 to a weighted lever 48, the end of which is connected by means of a link 49 with a lever 50 on a short shaft 51, the inner end of which has a trip lever 52, which is engaged by the cross head on its downward movement. A sprocket 53 is mounted on shaft 39 and by means of a sprocket chain 54 communicates motion to a worm lifting gear 55, cables from which are attached to rings 56 fixed to cross head 19. Shaft 39 has also tight pulleys 57 and loose pulleys 58 and 59 over which run straight belt 60 and cross belt 61.

The bottom of vat 1 may be provided with a filter and may have a central opening 62 below which a conveyer 63 may be supported upon idlers 64.

To frame 28, by means of bracket 66 may be attached one or more vertical scrapers 67, it being understood that these scrapers may be attached at pleasure throughout the length of frame 28 and that the scrapers, if desired, may be set an angle to their direction of travel.

The mode of operation is as follows: The vat 1 being full of any material which it is desired to discharge therefrom, the traveling structure is run along the rails 4 until the central shaft 9 is over the opening 62 of the vat. The belt 60 is then run on to the tight pulley 57 by means of which the hoisting gear 55 will be operated to lower the cross head 19, shaft 9 and frame 28, carrying the disks 30, 31, 32, 33 and 35, until the disks contact with the surface of the material in the vat. The belt 60 is thereupon returned to its loose pulley. Clutch 26 now being thrown in, motion is communicated to shaft 9 carrying the disks around over the surface of the material. Owing to the angle at which the disks are set, they excavate the material and move it toward the center of the vat and discharge it through the central opening 62 on to the conveyer 63 which may carry it to any desired place.

The crank 36 operates lever 38, which, by means of pawl 40 imparts motion to ratchet 43, thereby through the mechanism previously described, allowing the disks to follow the material as its level is

lowered in the vat. The rate of this vertical motion may be adjusted by varying the length of the throw of crank 36. When the excavating disks 30, 31, 32, 33 and 35 near the bottom of the vat, cross head 19 contacts with tripper lever 52, thereby drawing down lever 50 and link 49 and throwing weighted lever 48 to the left and drawing clutch 45 out of engagement and stopping the further movement of the hoisting gear.

If the contents of the vat are not equally divided between the two sides, the scraper 67 is attached to frame 28. The revolution of the frame 28 will cause the material to be removed from the point where there is a super-abundance and deposit it where the material is lacking. The rotation of shaft 9 may be reversed to distribute the material in tank 1 by moving it away from the center.

Claims

1. A plurality of rotating cutters revoluble around a common center and placed at an angle to their direction of travel and also at an angle to the vertical and means for operating said cutters.

2. A plurality of concavo-convex cutters revoluble around a common center and placed at an angle to their direction of travel and also at an angle to the vertical and means for operating said cutters.

3. A plurality of cutters revoluble around a common center and placed at an angle to their direction of travel and at an angle to the vertical, said latter angle being greatest in the cutters remote from said center.

4. A plurality of rotating cutters revoluble around a common center and placed at an angle to their direction of travel, certain of said cutters being at an angle to the vertical also, and means for operating said cutters.

5. A plurality of rotating cutters revoluble around a common center and placed at an angle to their direction of travel, certain of said cutters being flat and others being concavo-convex and set at an angle to the vertical.

6. A plurality of rotating cutters revoluble around a common center and placed at an angle to their direction of travel and also at an angle to the vertical, the operating portion of said cutters being nearest said center, and means for operating said cutters.

7. A plurality of rotating cutters revoluble around a common center and placed at an angle to their direction of travel and also at an angle to the vertical, the operating portion of a majority of said cutters being nearest said center and a cutter having its operating portion remote from said center and means for operating said cutters.

8. A plurality of rotating cutters revolving around a common center and placed at an angle to their direction of travel and also at an angle to the vertical and means for raising and lowering said cutters into and out of operating position.

9. A plurality of rotating cutters revolving around a common center and placed at an angle to their direction of travel and also at an angle to the vertical and automatic means 5 for raising and lowering said cutters into and out of operating position.
10. A series of excavating cutters revolving around a common center and a scraping disk set at an angle to the vertical.
- 10 11. A series of excavating cutters revolving around a common center and a scraping disk set at an angle to the vertical and also to its direction of travel.
12. A series of excavating cutters revolving 15 around a common center, and a scraping disk set at an angle to the vertical, the operating portion of said scraping disk being farthest from said center.
- 20 13. A series of excavating cutters revolving around a common center and a scraping disk set at an angle to the vertical and also to its direction of travel, the operating portion of said scraping disk being farthest from said center.
- 25 14. A traveling structure, a shaft mounted in the central part thereof, an excavator operated by said shaft, a cross head supporting said shaft, a lifting gear attached to said cross

head, a clutch operating said lifting gear and mechanism operated by the vertical movement of said excavator to release said clutch. 30

15. A traveling structure, a shaft mounted in the central part thereof, an excavator operated by said shaft, a cross head supporting said shaft, a lifting gear attached to said cross 35 head, a weighted lever connected with said clutch, a lever connected to said weighted lever and a contact lever adapted to engage said cross head.

16. In hydro-metallurgical apparatus a series of vats, rails at the sides thereof, a traveling structure on said rails, an excavator supported on said structure, means for rotating, raising and lowering said excavator and automatic means for stopping the vertical 45 movement of said excavator.

In testimony whereof, I have signed my name to this specification, in the presence of two subscribing witnesses at Los Angeles in the county of Los Angeles, State of California, 50 this 18th day of May A. D. 1906.
